COMBINED BELT AND GARMENT

Alfred S. Kaufman, New York, N. Y., assignor to
 Alseka Clothing Company, Inc., New York,
 N. Y., a corporation of New York

Application December 23, 1949, Serial No. 134,744

1 Claim. (Cl. 2-237)

1

This invention relates to new and useful improvements in a combined belt and garment, and, more particularly, the aim is to provide a novel and valuable such combination characterized by the inclusion in the belt component of markedly few and exceedingly simple parts, with these parts correlated in such manner that the belt may be readily and quickly opened and closed, thereby to open and close the garment, and also correlated in such manner that the waist portion of the garment may be very snugly yet comfortably fitted to and all around the body of the wearer, yet then with the waist portion of the garment and its belt addition, as these ordinarily would be viewed, quite conventional in appearance.

The invention as herein illustrated is applied to a pair of trousers, but, as will be understood, it is with like advantages also applicable to slacks, skirts and the like.

One of the features of the invention, additional to those already mentioned, is that a slideable belt member does not have to be employed, either at the inside or outside of the waist portion of the garment; another such feature is that while an elastic belt member is employed, the major width thereof is neither at the inside nor at the outside of the garment, but, instead, such major width portion is present as a fully girthwisely extending upward prolongation of the upper limit of the garment; another such feature is the combination with the said elastic belt member of a minor complementary belt structure in the form of two bucklably connectible inelastic belt sections, each fixedly attached to the outer side of the elastic belt member at the end of said inelastic section remote from its end to be bucklably connected to the other such section.

Another feature is the inclusion of dual fastening means for the ends of the belt component at the front center of the garment, with said fastening means consisting in part of the buckle means of said inelastic sections and in part of a fastening means for the ends of the elastic belt member, and with said two fastening means so relatively disposed that when the buckle means is closed, following closing of the fastening means for the ends of the elastic belt member the last-named fastening means is wholly concealed.

For further comprehension of the invention, and of the objects and advantages thereof, reference will be had to the following description and accompanying drawings, and to the append-

2

ed claim in which the various novel features of the invention are more particularly set forth.

In the accompanying drawings forming a material part of this disclosure:

5 Fig. 1 is fragmentarily a front perspective view of a pair of trousers equipped with a now approved embodiment of the belt component of the new combination.

10 Fig. 2 is an enlarged vertical detail section, taken on the line 2-2 of Fig. 1.

Fig. 3, drawn to about the same scale as Fig. 2, is a fragmentary collective view, illustrative of the front portion of the combined belt and garment, with the end portions of both parts of 15 the belt component detached, and consequently with both said fastening means opened.

Fig. 4 is a view similar to Fig. 2, illustrating a modification.

Referring now to the drawing more in detail, 20 the pair of trousers illustrated at 10 is shown as having the usual front fly 11, so that, as is customary, this garment may be widely opened at the front thereof and below its top. Such top, in the present case, is shown, at 12, as being placed at about the usual location of the bottom edge of the conventional outer endwisely slideable leather belt held at the waistband portion of trousers of the ordinary cut by way of a plurality of belt-loops spaced around the 25 trousers top.

The aforesaid elastic belt member, this designated 14, is suitably secured, all along its length and at its lower marginal portion, as by stitching as indicated, to the inside of the trousers 30 10, with its said lower marginal portion inside the trousers and with the bottom edge of the belt 14 slightly below the top 12 of the trousers. This belt member 14, desirably a length of elastic strip material woven to be selvaged along opposite sides, is shown as finished off at its opposite ends by inturning such ends and stitching the inturned portions as shown to provide at one end of the belt member a two-ply structure 35 15 and at the other end of the belt member a two-ply structure 16. Stitching of the belt member 14 to the trousers while said member is in stretched condition results in the trousers material adjacent to the trousers top 12 becoming suitably gathered, as at 14^a, so that later stretch 40 50 of the belt member 14 longitudinally thereof will be permitted because accompanied by a corresponding increase in the length of the trousers top 12 due to opening up of such gathers.

As aforesaid, a minor complementary belt structure constitutes, in combination with the

elastic belt member 14, the complete belt component. Of said minor structure, its two inelastic belt sections, these respectively marked 17 and 18, are herein shown as straps, as of leather or the like.

Said strap 17 has an enlarged end, and at such end said strap is fixedly attached, as by a stitching 19, to the outer side of the end portion of the elastic belt member 14 adjacent to the two-ply structure 15 but at some distance back from said structure. The strap 18 has a similarly enlarged end, and at such end this strap is fixedly attached, as by a stitching 20, to the outer side of the end portion of the elastic belt 14 adjacent to the two-ply structure 16 but at some distance back from said structure.

The strap 17 beyond its said enlarged end is extended toward the strap 18 by a tongue prolongation having spaced therealong a plurality of holes 21. The strap 18 beyond its said enlarged end is extended toward the strap 15 by a tongue-like prolongation folded back on itself near its outer end for there mounting a buckle 22, as in the manner and by the stitching indicated.

These elements 21 and 22 constitute the aforesaid bucklably connectible fastening means between the two inelastic belt sections; which sections, as just explained, are constituted by the straps 17 and 18.

Said straps are desirably of such lengths that when a person wearing the new combined belt and garment is frontally casually glanced at, especially if such person be wearing a coat or jacket, the visual effect will be substantially that of a person wearing an ordinary pair of trousers in association with an ordinary separate waist encircling belt.

Any selected decorative addition, as one mounting an imitation gem, is shown at 23 as fixedly attached to each of the straps 17 and 18 at their enlarged ends; and, particularly, with such or equivalent additions included, the elements 14, 17, 18, 22 and 23, taken together as a visual ensemble while the trousers are being worn, suggest rather that the trousers are ordinary ones, and that the belt component as a whole, although especially embellished, is an ordinary belt.

The elastic belt member 14 is always smartly erect all around the waist of the wearer. The means for insuring this includes the aforesaid fastening means partially carried by each of the opposite ends of the member 14; said means being herein shown as comprising a button 24 stitched to the outside of the two-ply structure 15 and a button-hole cut 25 and worked through the two-ply structure 16. In use, said fastening means 24-25 is first closed, and following this, the tongue of the strap 17 is engaged with the buckle 22 at that one of the holes 21 for drawing together the two straps 17 and 18 to flatness against the belt member 14 and into longitudinal alignment across the front of the belt component. Now, also, the fastening means 24-25 is wholly concealed.

Referring to the modification shown in Fig. 4, all the above advantages are retained, but, in addition, the elastic belt member, here marked 14',

is so permanently attached to the top of the trousers 10' or the like that such permanent attachment may be later modified for holding the parts 10' and 14' still permanently connected, yet for raising the general level of the belt member 14' thereby to improve when required the fit of the garment above the hips of the wearer. The belt member 14' along its bottom is twice reversely laterally bent on itself, to present a bottom marginal structure which is of three-ply nature because it includes the folds 26 and 27. In fabricating the garment, two lines of stitching are applied all along the length of the belt member 14'. One of these stitchings, 28, is for attaching the belt member along its fold 26 to the trousers material; and the other of these stitches 29, is sent through both the folds 26 and 27 near the bottoms thereof, as well as through the trousers material.

During establishment of each of these stitchings 28 and 29, as in the case of the stitching of the belt member 14 to the trousers 10 in Figs. 1-3, the belt member 14' is in stretched condition, and the trousers material is suitably gathered, as at 14'. At any time later, as after a first try-on, or even after some period of use of the new garment, the belt member 14' may be given a greater width, so as to raise its top higher above the top of the trousers, merely by cutting free various of the thread loops of the stitching 29 and entirely removing this stitching.

While I have illustrated and described the preferred embodiments of my invention, it is to be understood that I do not limit myself to the precise constructions herein disclosed, and the right is reserved to all changes and modifications coming within the scope of the invention as defined in the appended claim.

Having thus described my invention, what I claim as new, and desire to secure by United States Letters Patent is:

In a garment of the trouser type having a fly opening extended downward from the top edge thereof and an elongated elastic member of a length corresponding to the circumference of the top edge of the garment secured along its bottom edges to the top edge of the garment, said elastic member having its free ends overlapped over the fly opening, and aligned non-elastic belt members secured at their outer ends to the elastic member on opposite sides of said overlapped ends, means releasably securing together said overlapped ends of the elastic member, and means releasably securing together the inner ends of said belt members.

ALFRED S. KAUFMAN.
